LIQUID APPLICATOR MOP

Vito J. Cassata, Flushing, N. Y.

Application July 12, 1954, Serial No. 31,392

Term of patent 14 years

(Cl. D9—2)

Fig. 1 is a side elevational view of a liquid applicator mop, showing my new design;

Fig. 2 is an enlarged fragmentary elevational view of the top portion of the applicator handle; and

Fig. 3 is an enlarged fragmentary perspective view of the lower portion of the applicator.

I claim:

The ornamental design for a liquid applicator mop, as shown.
